UNITED STATES PATENT OFFICE

FRANCIS L. BRANDT, OF WAKEFIELD, MASSACHUSETTS, ASSIGNOR TO UNITED SHOE MACHINERY CORPORATION, OF PATERSON, NEW JERSEY, A CORPORATION OF NEW JERSEY

METHOD OF AND MEANS FOR USE IN LOCATING SHANK PIECES

Application filed May 23, 1932. Serial No. 612,963.

This invention relates to improvements in methods of and means for use in locating shank pieces of the type wherein an aperture is provided for the reception of a heel-attaching screw.

In United States Letters Patent No. 1,615,258, granted Jan. 25, 1927 upon application of M. V. Bresnahan, there is disclosed a method of attaching heels which involves the use of a last having a hole or perforation extending through its rear portion from the top of the cone to the bottom of the heel seat and which comprises the following steps or operations, viz., assembling an upper and an insole on the last, pulling-over and lasting the upper and securing it to the insole, laying an outsole, positioning a heel upon the shoe, and passing a drill through the hole in the last and operating it to bore holes through the soles and into the heel in line with the hole in the last in preparation for the insertion through the last and into the heel of a screw-fastener for temporarily clamping together the last, the shoe and the heel and for the subsequent insertion of a wood screw from the inside of the shoe for permanently securing the heel to the shoe. In a copending application, Serial No. 419,666, filed Jan. 9, 1930, in the name of F. C. Ayling, the above-described method of heel attaching is disclosed as being practised in connection with the manufacture of shoes of the type wherein a shank stiffener extends rearwardly to a point located above the heel, and a permanent heel-attaching screw extends through, and fits snugly within, a circular aperture in the rear portion of the shank stiffener so as to provide a rigid connection between the stiffener and the heel as well as to secure the heel to the shoe. In the method disclosed in the Ayling application just referred to, the method of attaching heels disclosed in the above-mentioned Letters Patent No. 1,615,258 is further modified to the following extent, viz.,—before the shank piece is applied to the shoe a heel-fastener-receiving aperture is formed in the insole by means of a drill passed through the hole in the last, and thereafter

the fastener-receiving aperture in the shank stiffener is located relatively to the hole in the insole by means of a tapered wooden peg which is driven through the aperture in the stiffener and into the holes in the insole and the last and later, during the operation of drilling a hole in the heel, the drill operates also to drill out the wooden peg and thus to reopen the hole previously formed in the insole as well as to drill through the outsole and into the heel.

One object of the present invention is to secure the various advantages of the method of shoe making disclosed in the Ayling application above-referred to while making it still easier to locate a shank stiffener with its aperture suitably positioned for the passage of a drill and a heel-attaching fastener therethrough.

With this object in view, the invention 70 contemplates an improved method of making shoes which, considered in one aspect, comprises forming an integral locating projection on a shoe sole, and locating an apertured reinforcing member relatively to the 75 sole by positioning the reinforcing member with the projection on the sole extending into the aperture in the reinforcing member. Thereafter, as illustrated, the reinforcing member is secured in its located position 80 and a hole is made in the sole in line with the aperture in the reinforcing member, thereby removing the locating projection and preparing the sole for the reception of a fastener which is to extend also through the 85 aperture in the reinforcing member.

As herein exemplified, in connection with the manufacture of a shoe upon a last having a hole extending from the top to the bottom of its heel portion, the locating projection is formed in an insole on the last by means of an elongated spindle, having a free extremity which is shaped to constitute a forming or molding member and which is passed through the hole in the last into engagement with the inner side of the insole and is forced into the insole material to form a projection upon the outer side of the insole. Accordingly, it is to be recognized that invention resides also in that 100

step in the art of making shoes which comprises operating from the inside of a shoe on a perforated last to form a projection on the outer side of the insole of the shoe, 5 for use in locating an apertured reinforcing member such as a shank stiffener with the aperture in the reinforcing member in line with the perforation in the last. As herein illustrated, the projection-forming extremity of the spindle co-operates with a complementary forming member in engagement with the outer side of the insole in forming the projection, the complementary member serving to support the insole against 10 the thrust of the spindle.

After the reinforcing member or shank stiffener has been located by means of the projection and has been secured in place upon the insole and in accordance with the 15 improved method as herein exemplified, the locating projection is cut away and a heel-fastener-receiving hole is formed in the insole in line with the fastener-receiving aperture in the shank stiffener by means of a 20 drill which is operated through the hole in the last. Thus both the hole in the insole and the aperture in the stiffener are accurately located in line with the hole or perforation in the last and in position to receive 25 a heel-attaching fastener. The outsole of the shoe may be laid before the drilling of the insole or, if desired, both the outsole may be laid and the heel attached to the shoe before the drilling operation is performed. 30 Thus the drill may be employed to form at a single operation a hole through the outsole and in the heel as well as a hole in the insole, and each of the holes so formed will be aligned with the aperture in the shank 35 piece and with the hole in the last preparatory to receiving a heel fastener which will pass also through the hole in the shank stiffener and will thus co-operate with the shank stiffener to stiffen the shank and brace 40 the heel as well to serve as a permanent means for attaching the heel to the shoe.

Considered in another aspect invention is to be recognized as residing in novel apparatus for use in carrying out the above-described method, the illustrated apparatus comprising complementary forming members one of which is constructed and arranged to engage the outer face of a sole mounted upon a perforated last to support the sole and the 55 last, and the other of which is constructed and arranged to extend through a perforation in the last and to cooperate with the first member to form a locating projection in the outer face of the sole.

60 The invention will be explained with reference to the accompanying drawing, in which

Fig. 1 is a view partially in side elevation and partially in section of a projection-forming device adapted to be used in carry-

ing out the present method, the apparatus being shown in operation upon the insole of a shoe mounted on a perforated last;

Fig. 2 is a side elevational view of a portion of the device shown in Fig. 1 showing the parts in different positions from those shown in Fig. 1;

Fig. 3 is a perspective view of a perforated shank piece of the type adapted for use in co-operation with a heel attaching screw for bracing the heel and stiffening the shank portion of a shoe;

Fig. 4 is a perspective view of a shoe as it appears after the shank piece has been laid and positioned by means of a projection formed in the insole of the shoe;

Fig. 5 is a detail sectional view on an enlarged scale taken along the line V—V of Fig. 4; and

Fig. 6 is a sectional view of the rear portion of a shoe on a perforated last illustrating the step of removing the shank piece locating projection formed in the insole of the shoe.

The improved method of locating perforated shank pieces is herein illustrated as being practised in connection with the manufacture of a shoe on a perforated last such as the last disclosed in the above-mentioned Bresnahan patent. As shown in the drawing, a last A of the type referred to is provided with a hole B which extends through the heel portion of the last from the top of the cone to the bottom of the heel seat surface. After a shoe upper C and an insole D have been assembled upon the last A and the upper has been pulled-over and lasted to the insole in a customary manner, as shown in Fig. 1, a shank piece locating projection E is formed on the outer side of the insole in line with the hole B in the last by means of the apparatus shown in Figs. 1 and 2, such apparatus comprising a spindle 10 adapted to be passed downwardly through the hole B in the last and to operate from the inside of the shoe to form the projection E. In the illustrated apparatus the spindle 10 is of a diameter adapted to pass freely through the hole B in the last and to be guided by the latter so as accurately to determine the location of the projection on the insole. As shown, the spindle 10 is provided with a reduced lower extremity 12 shaped to co-operate with a lower member 14 in forming the projection E, the reduced extremity 12 and the member 14 constituting respectively the upper and lower members of a molding or projection-forming couple between which the insole is interposed.

The lower member 14 of the projecting-forming couple is formed with a stem 16 which is received in the upper portion of a bore 18 in a block 20 which in turn is secured by means of a set screw 22 within

- the recess in a table 24 which surmounts a pedestal 26. A thumb screw 28 is threaded in the bore 18 beneath the lower couple member 14 for supporting the latter and adapting it for up and down adjustment according to the thickness of the insole to be operated upon to adapt it to co-operate effectively with the extremity of the spindle 10 in forming the projection in the insole.
- 10 The spindle 10 which carries the upper member 12 of the projection-forming couple is secured at its upper end by means of a set screw 30 to a cylindrical block 32 which is slidably mounted within a tubular guideway 34, the latter being rigidly supported between frame members 35 which extend upwardly from the table 24, and carrying at its lower end a bushing 36 through which the spindle 10 is adapted to slide. The sliding block 32 which carries the spindle 10 is adapted to be moved up and down within the tubular guideway 34 by means of toggle mechanism comprising a link 38, the lower end of which is pivoted at 40 to the slide block 32 and a link 42 which is connected by a fixed pivot 44 with the upper end of the guideway 34 and which is pivotally connected at 46 with the link 38. For operating the toggle links 38, 42 a rearwardly extending arm 48 on the link 42 is pivotally connected at 50 to the upper end of a rod 52, the lower end of which is adapted to be connected with a foot treadle (not shown) by means of which the rod 52 may be lowered for the purpose of straightening the toggle and forcing the spindle 10 downwardly through the hole in the last into a position for causing the couple members 12 and 14 to co-operate in the formation of the projection E in the insole. A spring 54 connected at its upper end with the frame members 36 and at its lower end with the treadle rod 52 is provided for breaking the toggle.
- 45 In using the above-described apparatus, a perforated last of the type hereinbefore referred to, having a shoe upper and an insole assembled thereon, (is placed in position to be operated upon by introducing its heel portion between the upper and lower projection forming members 12 and 14, the last being held by the operator substantially in the position in which it appears in Fig. 1, and the spindle 10 which carries the upper forming member 12 being at this time in the raised or inoperative position shown in Fig. 2. The operator then depresses the treadle connected with the rod 52 thereby operating the toggle links 42, 38 to lower the spindle 10 until the upper forming member 12 at the lower extremity of the spindle enters the hole B in the last. Continued depression of the treadle moves the spindle 10 downwardly through the hole in the last and finally causes the upper forming mem-
- ber 12 to engage the insole and co-operate with the cavity in the lower forming member 14 to form the projection E in the insole. As shown, the spindle 10, while it is adapted to pass freely through the hole in the last nevertheless substantially fills that hole so that no play is permitted within the hole. Consequently, the projection formed in the insole will be located in accurate alignment with the hole in the last. The mold members 12 and 14 are shaped so that the projection E will present a smooth rounded contour adapted readily to enter a heel-fastener-receiving hole in a shank piece which is to be incorporated in the shoe.
- 50 A shank piece of a type particularly adapted for use in welt shoes is shown in Fig. 3, the shank piece being of composite construction consisting of a metallic shank 85 stiffener strip F and a filler piece G which may be made of leather, leatherboard or the like and to which the metallic strip F is secured by means such, for example, as staples H. The illustrated shank piece has the usual longitudinal curvature corresponding to the longitudinal curvature of the last bottom and a hole or aperture is formed in the rear portion of the shank piece, the hole being arranged to register with a corresponding hole in the rear portion of the filler piece G so that a heel-fastener-receiving hole I is formed which extends through both the strip F and the filler piece G. For use in shoes other than welt shoes it may be desirable to employ a shank piece consisting merely of a metallic strip such as the strip F, the strip having a heel-fastener-receiving aperture in its rear portion but having no filler piece associated therewith.
- 55 In assembling the shank piece with the shoe, the shank piece is laid upon the outer face of the insole D in such a position that the projection E which has been formed in the insole will extend through the heel-fastener-receiving hole in the shank piece thereby accurately locating the shank piece with the hole in alignment with the hole B in the last. The shank piece is then fixedly secured in place on the shoe bottom, for example by means of tacks K which may be driven through the filler piece G and into the insole.
- 60 The projection E, having performed its function of locating the shank piece, is in accordance with the present method, removed, either before or after the heel is attached to the shoe. As shown in Fig. 6 the projection E may be removed before attachment of the heel by means of a drill L which is passed downwardly through the hole B in the last and which is operated to cut away the projection E thereby forming a hole through the insole in line with the hole in the last. In Fig. 6, the outsole is shown as

having been laid prior to the performance of the above-described drilling operation and the drill operating to form a hole in the outsole M as well as in the insole. If a heel 5 is attached before any drilling operation is performed the drill may be utilized to form, at a single operation, fastener receiving holes in both soles and in the heel, in addition to removing the locating projection on 10 the insole. Inasmuch as the drill is guided by the hole in the last and inasmuch as the hole in the metal stiffener strip F has previously been located in accurate registration with the hole in the last the drill will not 15 engage the metal in the stiffener strip and consequently there is no danger of breaking the drill. After a hole has been drilled in the heel and the last has been pulled a permanent heel-fastener in the form of a wood 20 screw may be inserted from the inside of the shoe, the screw passing through the holes in the insole, the shank piece, and the outsole and being screwed into the heel. There is, of course, no danger that the threads will 25 be stripped from the screw by engagement with the metal of the shank stiffener inasmuch as the hole in the latter has already been positioned in accurate registration with the holes in the inner and outer soles and 30 ing the heel.

The invention having been described, what is claimed as new and desired to be secured by Letters Patent of the United States is:

1. That improvement in the art of making 35 shoes which comprises forming an integral locating projection on a shoe sole, and locating an apertured reinforcing member relatively to the sole by positioning the reinforcing member with the projection on the sole 40 extending into the aperture in the reinforcing member.

2. That improvement in the art of making 45 shoes which comprises forming an integral locating projection on a shoe sole, locating an apertured reinforcing member relatively to the sole by positioning the reinforcing member with the projection on the sole extending into the aperture in the reinforcing member, securing the reinforcing member to 50 the sole, and makng a hole in the sole in line with the aperture in the reinforcing member thereby removing said locating projection and preparing the sole for the re- 55 ception of a fastener which is to extend also through the aperture in the reinforcing member.

3. That step in the art of making shoes 60 which comprises operating from the inside of a shoe on a perforated last to strike up a projection on the outside of the insole of the shoe for use in locating an apertured shank stiffener with the aperture in line with the perforation in the last.

4. That improvement in the art of mak- 65 ing shoes which comprises operating from

the inside of a shoe on a perforated last to strike up a projection on the outside of the insole of the shoe for use in locating a perforated shank piece in line with the perforation in the last, assembling a shank piece by placing the perforation therein over the projection in the insole, attaching the shank piece to the insole, and thereafter operating through the perforation in the last to remove the locating projection in the insole 70 and form a hole in the insole in line with the perforation in the last. 75

5. That improvement in methods of making shoes which consists in passing one member of a projection-forming couple through a hole in a last in a shoe to locate the last with said hole in line with the other member of the couple, operating the members of the couple to form a projection on the insole of the shoe, and utilizing the projection in conjunction with a heel-fastener-receiving hole in a shank piece to locate the shank piece 80 relatively to the insole of the shoe. 85

6. That improvement in methods of making shoes which consists in securing an insole to a last having a hole extending through its heel portion from the top of the cone to the bottom of the heel seat, forming an outwardly directed projection on the insole in line with the hole in the last, laying 90 upon the insole a shank piece having a heel- fastener-receiving aperture therein, and positioning the shank piece by locating said aperture over the projection on the insole. 95

7. That improvement in methods of making shoes which consists in securing an insole to a last having a hole extending through its heel portion from the top of the cone to the bottom of the heel seat, forming an outwardly directed projection on the insole in line with the hole in the last, laying 100 upon the insole a shank piece having a heel- fastener-receiving aperture therein, positioning the shank piece by locating said aperture over the projection on the insole, and forming a heel-fastener-receiving hole 105 through the insole in line with the hole in the last, thereby removing said projection. 110

8. That improvement in methods of making shoes which consists in securing an insole to a last having a hole extending through its heel portion from the top of the cone to the bottom of the heel seat, forming an outwardly directed projection on the insole in line with the hole in the last, laying 115 upon the insole a shank piece having a heel- fastener-receiving aperture therein, positioning the shank piece by locating said aperture over the projection on the insole, laying an outsole and securing it to the shoe, inserting a drill in the hole in the last and passing it downwardly through the insole, through the hole in the shank stiffener, and through the outsole, thereby forming holes 120 in the insole and outsole in line with the 125

130

holes in the last and the shank stiffener, and cutting away the projection on the insole.

9. A machine for forming locating projections on shoe soles comprising a member adapted to operate through a hole in a last having a sole mounted thereon to form a locating projection on the sole, and means for supporting the sole and the last and for operating the projection-forming member.

10. A machine for forming locating projections on shoe soles comprising co-operating forming members adapted to receive a shoe sole between them, one of said members being constructed and arranged to operate through a hole in a last upon which the sole is mounted, and means for relatively moving said forming members to form on the face of a sole on a last a locating projection in line with the hole in the last.

11. A machine for forming locating projections in shoe soles comprising supplemental forming members one of which is constructed and arranged to engage the outer face of a sole mounted upon a perforated last to support the sole and the last, and the other of which is constructed and arranged to extend through a perforation in the last and to co-operate with the first member to form a locating projection on the outer face of the sole.

12. A machine for forming locating projections in shoe soles comprising supplemental forming members one of which is constructed and arranged to engage the outer face of a sole mounted upon a perforated last to support the sole and the last, and the other of which is constructed and arranged to extend through a perforation in the last and to co-operate with the first member to form a locating projection on the outer face of the sole, and means for relatively adjusting the forming members to accommodate soles of different thicknesses.

45 13. A machine for operating upon soles mounted upon perforated lasts comprising a molding couple consisting of a member constructed and arranged to engage the outer face of a sole on a perforated last and a member constructed and arranged to extend through a perforation in the last to engage the inner face of the sole and to co-operate with the first member in forming a projection on the outer face of the sole, and means for operating one of the members of said couple to move said member into co-operative relation with the other member.

60 14. A machine for forming a locating projection on a sole mounted on a last having a hole extending through its heel portion from the top of the cone to the bottom of the heel seat face comprising a spindle adapted to extend through the hole in the last and having a projection-forming ex-

tremity, a member having a molding cavity disposed in the path of said spindle for co-operating with said extremity of the spindle to form a projection on the insole, and means for relatively moving the spindle and said member to and from co-operative projection-forming relation.

15. A machine for forming a locating projection on a sole mounted on a last having a hole extending through its heel portion from the top of the cone to the bottom of the heel seat face comprising a spindle adapted to pass through the hole in the last and having a free extremity shaped to form a projection in the sole, means for supporting the last and the sole by engagement with the sole, said means having a molding cavity disposed in the path of said spindle for co-operating with the spindle to form a projection on the insole, and toggle mechanism for operating said spindle.

In testimony whereof I have signed my name to this specification.
